VALVE GRINDING MACHINES

Marvin H. Humbert, Cedar Rapids, Iowa, assignor to Cedar Rapids Engineering Company, Cedar Rapids, Iowa, a corporation of Iowa

Filed Aug. 7, 1959, Ser. No. 832,313

1 Claim. (Cl. 51—95)

This invention concerns a valve grinding machine and more particularly one in which the grinding wheel rotates in a horizontal plane and the work piece is lowered vertically into contact with the wheel.

In valve grinding machines of the type commonly used in automotive service shops, the grinding wheel rotates in a vertical plane and the work piece is moved horizontally into contact with the grinding wheel. The various required adjusting movements are made in the horizontal plane.

In such devices, the vertical grinding wheel is usually positioned towards the back of the machine and the motor, which rotates the chuck holding the work piece, is positioned up towards the front of the machine. This necessarily places the operator at a distance from the actual work area and his view of the work being done is in this way restricted to some extent and, in addition, he is in the plane of rotation of the grinding wheel and exposed to some danger by reason of chips or flying particles that may be thrown outwardly from the wheel.

Therefore the primary object of this invention is to provide a device in which the grinding wheel is positioned in a horizontal plane well below eye level to permit the work piece to be brought vertically downward into contact with the grinding wheel.

It is a further object of this invention to provide a device in which the work piece may also be swung in a horizontal arc into contact with the grinding wheel.

It is yet another object of the invention to provide a device in which the work piece may be swung in a vertical arc in relation to the grinding wheel.

It is yet another object of this invention to provide a device in which a second work piece holding fixture may be employed to swing the work piece in a horizontal plane to bring it into contact with the upper surface of the grinding wheel.

It is still another object of this invention to provide a device in which a plurality of work piece fixtures may be positioned on a single base to permit the work piece to be brought into contact with a single grinding wheel in a plurality of positions to permit the grinding of several faces of the work piece as may be required.

Other and further features and objects of the invention will be more apparent to those skilled in the art upon a consideration of the accompanying drawings and following specifications, wherein is disclosed a single exemplary embodiment of the invention, with the understanding, however, that such changes may be made therein as fall within the scope of the appended claims, without departing from the spirit of the invention.

In said drawings:

FIGURE 1 is a front view of a device constructed according to my invention.

FIGURE 2 is a cross sectional view, in part, of the device to show the means whereby the motor driven chuck mechanism may be raised and lowered in relation to the grinding wheel.

FIGURE 3 is an enlarged view of the lower portion of the motor driven chuck assembly.

FIGURE 4 is an enlarged view of the auxiliary valve holding fixture which is provided to facilitate the grinding of the ends of the valve, and

FIGURE 5 is a partial view of the device showing the

2

attachment which positions the rocker arm in relation to the grinding wheel.

Referring now to the drawings, and more particularly to FIGURE 1; a valve grinding machine constructed according to my invention includes a plurality of major assemblies which I will now describe.

A base member 11 includes a raised inner island portion 12 which is provided to house a motor driven grinding wheel 13, the wheel being positioned on its upper face and also to house the lower end of the chuck assembly supporting post which is indicated at 14. This post extends downwardly into the interior of the island base portion and can be rotated in a horizontal plane by a control wheel 15. The mechanism for the rotation of this post and the movement of the other assemblies will be described in greater detail hereinafter.

The post 14 carries a large sleeve assembly 16 which in turn carries a motor driven chuck assembly, indicated generally at 17. This sleeve member is adapted to be moved vertically on the post by the rotation of a control lever assembly, indicated at 18. The chuck assembly is also mounted on the sleeve by means of a stub shaft 39 in a manner which permits it to be rotated in relation to the shaft in a vertical plane and locked in a selected position by the rotation of the threaded clamp and lever, indicated at 19.

A second valve holding fixture 20 is also mounted on the same island portion 12 on the side opposite to the post 14. This second fixture is provided to hold the valve in a vertical position in relation to the grinding wheel.

To permit a better understanding of the device, I will first describe the function of the several elements and then the individual structure of each assembly.

Referring to FIGURE 3, it will be noted that the chuck 21 holds the stem of the valve at an angle of approximately 45 degrees in relation to the horizontal. It will be recalled that the grinding wheel is positioned in a horizontal plane. It will also be understood that this angle can be varied in either direction from the 45 degree mark 22, in relation to the vertical. It will be understood that this face is ground by the vertical face 23 of the grinding wheel.

The chuck 21 and the valve 24 held therein is rotated by an electric motor 25. The grinding wheel 13 is rotated at a high speed by a motor 27 which is positioned internally of the island base portion 12. In order to secure an even grinding operation, it is desirable to move the valve face continuously up and down in relation to the face of the grinding wheel. This action need not be closely controlled. Therefore it may be done manually.

It is for this purpose that the sleeve 16 is adapted to vertical movement on the post 14. The operator can keep this sleeve in continuous up and down motion by

rocking the control handle 18. In practice, the operator determines the proper angle of the valve face and adjusts the power driven chuck assembly by rotating the assembly on the sleeve 16, referring to the index 35 and 36 until it indicates the desired angle. He then brings the chuck and valve downwardly in relation to the grinding wheel until the valve face is in the same plane as the wheel.

As has been previously described, the post 14 is adapted to rotate about its vertical axis. Therefore, the valve can then be moved in a horizontal arc into contact with the vertical face of the grinding wheel.

The previously described control wheel 15 permits the operator to bring the valve into contact with the grinding wheel and to move it quickly away from the wheel as soon as it is apparent to him, by the appearance of the valve and the cessation of sparking, that the grinding operation has been completed.

Turning now to the second valve holding fixture 20; this fixture is adapted to hold the valve in a vertical position to permit the stem to be ground. The valve 24 is clamped in this fixture with the stem extending downwardly with the lower end in a parallel plane in relation to the upper surface 26 of the grinding wheel. The fixture then may be swung inwardly to a point where the valve stem is in line with the upper face of the grinding wheel. Once the valve is swung over the wheel, the lower end will then be ground.

A third fixture, indicated generally at 57, is mounted on the sleeve 16 and adapted to hold a rocker arm in position to be ground by the wheel 13. This structure is shown in detail in FIGURE 5. The structure comprises the slotted arm 57 which carries on its outer end a collar and shaft 59 and locking screw 60. The rocker arm 58 is positioned on the shaft and collar 59, the arm 57 moved to a position whereby the outer end of the rocker arm is over the grinding wheel. By the movement of the sleeve vertically and movement of the rocker arm in an arc about the collar and shaft 59, the rocker arm can be slightly rotated to facilitate the grinding of the boss on the rocker arm.

Turning now to the structure of the individual assemblies, as previously set forth, the post 14 is positioned in the island portion of the base and extends downwardly through this portion to the lowermost extremity of the base section. At this point the post is mounted on the thrust bearing 29 to permit its free rotation. Also positioned on this post is a gear 30 which in turn meshes with the worm gear 28 which in turn is rotated by the control handle 15. This permits the rotation of this post a full 360 degrees, although such action is not normally required for the operation of the device. However, it does permit easy accessibility for repairs and adjustment. The post also includes a gear rack 31. This in turn is meshed with a circular gear 32 which in turn is mounted on a shaft 33 which in turn is a part of the sleeve assembly 16 and is controlled by the handle 18. It is this gear and rack assembly which permits the sleeve to be moved vertically in relation to the post.

The sleeve 16 carries a face plate 34. The power driven chuck assembly 17 is mounted on this face plate. It will be noted that the face plate also carries a calibrated scale 35 which corresponds to a similar scale 36 on the face plate 37 of the chuck assembly. The chuck assembly is pivoted on the sleeve and adapted to rotate in relation to the face plate 34 of the sleeve 16. This chuck assembly comprises a base portion 38 which includes the previously mentioned face plate 37. A single horizontal shaft 39, as shown in FIGURE 3, serves as the pivotal connection between the sleeve and the chuck assembly. This base assembly 38 also includes a pair of electrical switches 39a and 40 which are actuated by the control handle 41. These switches control the chuck motor 25.

In this connection it will be noted, by reference to FIGURE 3, that the shaft 42a to which the handle 41 is connected has one flat face 44 which, when rotated in relation to the toggle switch handle 43, will cause the switches to be thrown back and forth to start or stop the motor.

The second valve holding fixture is mounted on the island portion of the base by means of a tubular bracket 45 which carries the lower end of a post 46. Mounted on this post is the vise assembly 47 which includes two jaws 48 and 49, the jaw 49 being controlled by a screw 50 and wheel 56. This vise assembly is adapted to be moved up and down in relation to the post 46.

Since the fixture 20 is provided to enable the operator to grind the base of a valve stem, it is necessary that this valve stem be positioned in relation to the upper horizontal face of the grinding wheel 26 to secure a minimum removal of metal. In order to secure the proper alignment, a gauge 52 is provided. This gauge is a threaded screw mounted on the island portion 12 at

one side of the grinding wheel. The operator turns this gauge until the upper surface is slightly below the level of the top face of the grinding wheel. The fixture 20 is then swung in an arc until the jaws 48 and 29 of the vise are just above the top surface of the gauge 52. The valve stem is then inserted with the base portion down until it comes into contact with the gauge 52. The vise is then tightened and the valve is in proper position. The fixture is then swung over the grinding wheel and as it contacts the upper surface of the wheel, the grinding operation begins.

The fixture 20 also carries an upwardly extending shaft 27a on which is positioned a support member 27b. This support member is adapted to hold the valve head 22 when it is positioned in the vise 47. This support member can be moved up and down on the shaft 27a and once the proper position of the valve has been fixed in reference to the grinding wheel by use of the gauge 52, the support member can be adjusted at a point where successive valves of the same size will be held in proper position relative to the wheel.

In the grinding operation it is necessary that a cutting oil or coolant be used. This fluid is directed onto the grinding surface by a tube 54 which arches up over the wheel. The oil is carried in a sump area 58 which is a cavity between the base 11 and the island 12. A pump 55 mounted in this cavity draws the oil out of the sump and forces it through the tube 54. This pump is driven by an electric motor.

Since there are three separate motors in the device, it is necessary that one central switch be provided to control all three motors, and this is mounted in the base section 11 as indicated by the numeral 53. The switches 39a and 40 are in series with this primary switch 53 and control only the chuck motor 25.

From the foregoing it will be apparent that a valve positioned in the chuck 21 can be moved in a vertical rectilinear path or swung in a vertical arc above the grinding wheel or swung in a horizontal arc about the vertical axis of the post, and in this manner a complete flexibility of control can be exercised over the grinding operation. It will also be apparent that this grinding operation takes place at a point immediately in front of and below the eye level of the operator and can be readily observed at all times.

It will further be apparent that the secondary fixture can be moved vertically in relation to the grinding wheel and also it can be swung in a horizontal arc in the same plane as the grinding wheel and that thereby a secondary grinding operation can be carried out in the same work area.

Although I have described a specific embodiment of my invention, it is apparent that modifications thereof may be made by those skilled in the art. Such modifications may be made without departing from the spirit and scope of my invention as set forth in the appended claim.

I claim as my invention:

A valve grinding machine comprising a base having a motor-driven grinding wheel positioned thereon, said grinding wheel adapted to rotate in a horizontal plane and having a vertical grinding surface, a rotatably mounted post extending vertically from said base and above said grinding wheel, a sleeve mounted on the upper portion of said post and adapted for vertical adjustment thereon, a first vertical face on said sleeve, a motor-driven chuck assembly having a second vertical face adjustably mounted on said first vertical face, said chuck assembly adapted to receive an object to be ground, a rack and pinion assembly on said sleeve and said post for moving said sleeve and chuck assembly in a vertical rectilinear path, means for swinging said chuck assembly in a vertical arc for aligning a surface of said object with said vertical grinding surface, scale means on said first and second vertical faces for indicating the relation-

ship between the surface of said object to be ground and said vertical grinding surface, gear means for manually rotating said chuck assembly about the vertical axis of said post in a horizontal arc which passes through the center of said grinding wheel, whereby the surface of said object may be brought into contact with said vertical grinding surface, and a slotted arm pivotally mounted on the lower portion of said sleeve, said arm adapted to secure a rocker arm in a generally horizontal position with its push-rod engaging end in contact with the upper horizontal surface of said grinding wheel, whereby vertical reciprocating movement of said sleeve on said post rocks said push-rod engaging end on said grinding wheel.
